POSTLESS BALUSTRADE

George M. Grady, Minneapolis, Minn., assignor to Hupp
Corporation, Cleveland, Ohio, a corporation of Ohio

Filed Feb. 10, 1964, Ser. No. 78,572

Term of patent 14 years

(Cl. D13—7)

FIGURE 1 is a side elevational view illustrating the postless balustrade of my present invention, the opposite side being identical;

The broken lines shown in FIGURES 1 through 4 are for illustrative purposes only.

I claim:

The ornamental design for a postless balustrade, as shown and described.
